UNITED STATES PATENT OFFICE.

WILLIAM H. WITT, OF PETERSBURG, VIRGINIA.

CLOTHESPIN.

1,314,998.

Specification of Letters Patent.

Patented Sept. 2, 1919.

Application filed March 31, 1919. Serial No. 286,327.

To all whom it may concern:

Be it known that I, WILLIAM H. WITT, a citizen of the United States, residing at Petersburg, in the county of Dinwiddie and State of Virginia, have invented certain new and useful Improvements in Clothespins, of which the following is a specification, reference being had to the accompanying drawings.

10 This invention relates to an improved clothes pin, and the invention in its broadest aspect aims to provide a clothes pin constructed of resilient wire, and being so constructed as to provide means, whereby the 15 spring arms will more efficiently resist a force, applied for the purpose of distorting the spring arms, and yet will not act to prevent the necessary yieldability of the arms and also will not prevent the clamping 20 action of the arms. To the contrary, the means will act to insure a firmer clamping action of the arms on the clothes line and the clothes.

The invention further aims to improve, 25 simplify, and for the above reasons render more practical the construction of clothes pin set forth, illustrated and claimed in the application for patent to Julius G. Strad- 30 der, filed December 5, 1917, Serial No. 205,579.

The construction of clothes pin in the aforesaid application embodies a free and unattached arm, which, while it has its advantages in some respects, it has been found 35 in other respects to be impractical. For instance a free and unattached arm as disclosed in this application may be pulled outwardly, in other words distorted laterally and the member between this arm and the 40 opposite arm may also be distorted. Very often children are very destructive, and it has been found that the clothes pin as set forth in the aforesaid application has been so distorted by children, that it has no further use. For instance, the free and unat- 45 tached arm, when bent laterally or distorted, which will permit other parts of the pin to be likewise distorted, in time renders the pin weak, to such an extent as to prevent

the clamping legs from performing the necessary clamping actions, when the pin is rebent to its normal shape.

In the present invention, it is the aim to provide a clothes pin constructed from a single length of spring wire, bent to form a body loop, one end portion beyond this loop terminating in a spring arm, which is interposed between the sides of an arm, which is in the form of a loop, the arch at one end of said arm loop acting to contact with the body loop, thereby reinforcing the loop arm, the terminal portion beyond the abutment arch of this arm loop terminating in means constituting an abutment for that portion of the body loop, whereby it merges into the spring arm, in order to reinforce the spring arm and prevent the same from being unduly bent.

While the design and construction at present illustrated and set forth is deemed preferable, it is obvious that as a result of a reduction of the invention to a more practical form for commercial purposes, the invention may be susceptible to changes and the right to these changes is claimed, provided they are comprehended within the scope of what is claimed.

The invention comprises further features and combinations of parts, as will be hereinafter set forth, shown in the drawings and claimed.

In the drawings:

Figure 1 is a perspective view of the improved clothes pin constructed in accordance with the invention, showing the same suspended on a clothes line.

Fig. 2 is a view in elevation of the clothes pin shown in Fig. 1, showing the clothes line in section.

Fig. 3 is a view in perspective showing a slightly modified form of construction, and in this figure the sides 6 and 10 of the loop arm are substantially straight at their upper portions.

Fig. 4 is a perspective view of a modified construction of clothes pin, in which construction the parts 11 and 12 are dispensed with, and the upper part of the side 10

terminates in the eye 11^a to receive the side 6^a of the loop arm.

Fig. 5 is a view in elevation of the structure of clothes pin shown in Fig. 4, showing the arms of the clothes pin slightly sprung apart as indicated by the arrows *a* and *b*.

Referring more especially to the drawings 1 designates a clothes pin as a whole, which 10 is constructed from a single piece of wire. The wire in order to form the clothes pin is bent to form a body loop 2, which is substantially in the form of a ring. One end of the wire beyond this body ring or loop, as 15 indicated at 3 is bent to form a spring arm 4, the end portion of which terminates in an eye 5.

The other end portion of the body loop or ring as at 6 is extended and is bent at 8, 20 so that the extended part 6, and bent portion 10 will form the opposite sides of a loop arm, and between which sides the spring arm is interposed. The side 10 is extended in tangential relation to the body 25 loop, and positioned across that portion of the loop, where the spring arm connects thereto. The side 10 at its upper end is bent at 11, arching over the body loop, and the part 12 beyond the bend 11 terminates 30 in an eye 13, through which that portion of the body loop where the spring arm extends from passes. By means of the bend 11 engaging near the upper part of the body loop, the loop arm is reinforced, and by 35 means of the eye engaging the bottom portion of the body loop at a point to abut the side 10, the spring arm is reinforced, thereby preventing the clamping arms of the clothes pin from being unnecessarily 40 distorted.

A modified form of construction of clothes pin is herein illustrated, and this particular design of clothes pin is also constructed of a single length of wire. 45 The wire is bent to form the body loop 2^b, and as in the first instance, a portion of the wire beyond the body loop is bent at 2^a to form the spring arm 3^a having a terminal eye 4^a. The opposite portion of the wire beyond the body 50 loop is bent to form the double-sided spring arm 6^a, and the terminal portion of the side 10^a of this double-sided spring arm 6^a terminates in an eye, extending at right 55 angles to the side 10^a, and this eye 11^a overlies the bend, thereby forming an abutment for the bend, and the spring arm which will offer a resistance when an attempt is made to unnecessarily distort the 60 spring arm. This eye 11^a receives that portion of the side of the double-sided loop arm, thereby insuring a loop arm having rigid sides, between which the spring arm

is interposed. It is to be observed that should force be applied to the extremities 65 of the spring arm and the double-sided loop arm in opposite directions, as indicated by the arrows *a* and *b*, the eye 11^a will be moved toward the bend, and the bend toward the eye, such parts abutting, consequently 70 limiting the movement of the spring arm and the double-sided loop arm.

The invention having been set forth, what is claimed as new and useful is:

1. A clothes pin, constructed from a single length of spring wire, the substantially intermediate portion of its length being bent to form a body loop, one end portion of the wire beyond the body loop being bent to form a double-sided loop arm, the other end portion beyond the body loop terminating in a spring arm interposed between the sides of the loop arm, one side of the double-sided loop arm terminating in means acting as an abutment for the bend between the spring 80 arm and a portion of the body loop, and means for reinforcing the first means.

2. A clothes pin, constructed from a single length of spring wire, the substantially intermediate portion of its length being formed into a body loop, one end portion of the wire beyond the body loop terminating into a double-sided loop arm, the other end portion of the wire beyond the body loop 90 engaging between the sides of the loop arm, and being bent and terminating in a spring arm interposed between the sides of the loop arm, one side of the double-sided loop arm extending tangentially with relation to the body loop and being bent to 95 form an arch arching over and abutting a portion of the body loop and terminating in a member overlying the opposite side of the body loop, said member terminating in an eye engaging a portion of the body loop, 100 said eye abutting against the opposite sides of the loop arm, thereby reinforcing the arms, and yet permitting of sufficient resiliency to permit the arms to separate.

3. A clothes pin, constructed from a single length of spring wire, the substantially intermediate portion of its length being bent to form a body loop, one end portion of the wire beyond the body loop being bent to form a loop arm extending tangentially to the body loop and having parallel 110 spaced sides, the other end portion beyond the body loop extending between the sides of the loop arm and terminating in a spring arm, said spring arm having its end portion 115 interposed between the lower parts of the sides of the loop arm, one of the parallel sides of the loop arm being extended upwardly and formed into the loop tangentially straddling a part of the body loop, the 120 extremity of one of the sides of this last 125

mentioned loop terminating in an eye, through which a portion of the body loop extends, to form a spring arm, at the point where the spring arm merges from between the parallel sides of the loop arm having a crotch for the reception of the clothes line, said eye at the terminal of one of the sides of the last mentioned loop coöperating with the sides of the loop arm and with a part

of the body loop, to govern the resiliency 10 of the loop arm and the spring arm during their separable actions.

In testimony whereof I hereunto affix my signature in the presence of two witnesses.

WILLIAM H. WITT.
